Attorney.

UNITED STATES PATENT OFFICE.

JEAN LOUIS LÉON ALEXANDRE ALBERT MOULET, OF PARIS, FRANCE.

DIAPHRAGM FUEL PUMP.

REISSUED

Application filed July 9, 1918, Serial No. 244,126, and in France June 4, 1917.

(GRANTED UNDER THE PROVISIONS OF THE ACT OF MARCH 3, 1921, 41 STAT. L., 1313.)

My invention relates to an improved regulating pump applicable to aerial machine motors.

In aerial machines and particularly in aeroplanes, in order to provide for the proper balancing of parts it is necessary that the supply of fuel should be placed below the carburetors of the motor requiring to be fed. This is particularly the case for aeroplanes having an extensive range of action on account of the heavy weight of fuel which it is necessary to carry. The result is that the fuel must be raised as fast as it is used by means of an auxiliary part acting as a pump.

The accompanying drawing which fully illustrates my invention shows a sectional plan of my improved regulating pump.

My improved regulating pump consists of an outer envelope or casing *a* an inner envelope *b* and framework forming a gear case *j*. This envelope *b* has a convex end and is provided with folds so as to be collapsible and extensible, and thus subject to deformation by elasticity in a direction perpendicular to the folds.

The liquid circulates between these two envelopes or casings which are connected in such a manner as to be thoroughly watertight. Upon the outer envelope are mounted two valve chests containing one a clack valve *f* opening in the direction of suction and the other a similar clack valve *m* opening in the forcing out sense. The inlet valve *f* is connected to the main fuel tank which will usually lie on a level below that of the carburetor and the outlet valve *m* is connected to the constant lever fuel tank of the carburetor.

A sliding rod *d* is screwed centrally at the convex end *b*¹ of the envelope *b* in a sleeve *b*² and is guided in a longitudinal sense, this rod being moreover recessed or hollowed out at *e*. The spring *g* is held at one end by the tension regulating device *h* and at the other by the hub of the gear case *j* while it is coiled around the sliding rod *d*. This spring which is suitably tightened has a tendency of maintaining the contact between the rear part of the recess *e* and an eccentrically journaled cam, whose journals turn in bearings formed integrally with the fixed part of the apparatus. Motion is imparted to

the cam *i* by a helicoidal pinion *s* gearing with the worm *t* keyed on the motor shaft 55 of the machine.

The pump operates as follows: as the cam turns in the direction indicated by the arrow the connecting rod is longitudinally displaced for half a turn, the spring *g* 60 is stretched the envelope *b* collapses, and the suction of the liquid takes place between the two envelopes *a* and *b*. As the cam *i* continues to rotate for another half turn, the spring *g* is distended and pushes the connecting rod in an opposite direction, the envelope *b* returns to its former position and the liquid is now forced out. The pump supply operated in the manner aforesaid is supposed to exceed the carburetor's consumption, the sucked up fuel gradually chokes the pump as the forcing out is incomplete, by reason of the incompressibility of the liquid, the spring is gradually tightened and the deformation of the envelope *b* increases. 70 The cam *i* breaks contact with the rod which ceases to have any effect on the suction until normal conditions prevail anew. The stroke corresponding to the feed is thus automatically regulated however such feed 75 may vary. The gear case *j* forming the framework contains all the moving parts and may be kept filled with oil.

Having now described my invention what I claim as new and desire to secure by Letters Patent is:

1. A diaphragm fuel pump, comprising in combination, an outer envelope, an inlet valve on said envelope adapted to be connected to a fuel supply, an outlet valve on 80 said envelope adapted to be connected to the constant level fuel tank of a carburetor, an inner collapsible and extensible envelope forming a liquid-tight joint with the outer envelope, a sliding rod secured to the inner 85 collapsible envelope, an eccentric cam adapted to positively move said rod in the direction corresponding to suction, means for operating said cam, and elastic means adapted to return the inner collapsible envelope in 90 the opposite direction.

2. A diaphragm fuel pump, comprising in combination, an outer envelope, an inlet valve and an outlet valve on said envelope, an inner collapsible and extensible envelope 105 forming a liquid-tight joint with the outer

envelope, a sliding rod secured to the inner collapsible envelope, an eccentric cam adapted to positively move said rod in the direction corresponding to suction, a shaft 5 carrying said eccentric cam, a worm wheel on said shaft, a worm in mesh with the worm wheel, a shaft carrying said worm, an oil-tight gear case in which the sliding rod and shafts are supported and containing the 10 eccentric cam and worm gearing, and elastic means adapted to return the inner collapsible envelope in the opposite direction.

3. In a diaphragm fuel pump, the combination of an outer envelope carrying two 15 valve chests containing each a check valve for the suction and forcing out of fuel respectively, an inner collapsible and extensible envelope forming a water tight joint with the outer envelope, framework forming a gear case, a longitudinal sliding rod guided by said gear case, an eccentrically journaled cam operating in a recess of said rod and rotated by worm gear mounted on the motor shaft, a longitudinal spring coiled on said 20 rod and urging the same back, and means for breaking contact between the cam and the sliding rod recess.

4. In a fuel-feeding system for engines, in combination, a pump casing adapted to 30 be operatively connected to the source of fuel and the fuel consuming elements of the engine, a flexible pumping member in said casing, means to positively flex said member to provide a suction stroke, and resilient means 35 coacting with said member in producing its pressure stroke.

5. In a fuel-feeding system for engines, in combination, a pump casing adapted to be operatively connected to the source of fuel 40 and the fuel consuming elements of the engine, an expandable and collapsible wall in said casing, means to positively actuate said wall in one direction to provide a suction stroke, and resilient means coacting with 45 said wall in the movement of the same in the opposite direction to provide a pressure stroke.

6. In a fuel-feeding system for engines, in combination, a pump casing adapted to be 50 operatively connected to the source of fuel and the fuel consuming elements of the engine, a flexible wall in said casing, and means comprising an engine-driven element operative to flex said wall in one direction

only, said wall moving in the opposite direction by the force of resiliency.

7. A fuel-feeding system for internal combustion engines comprising, a pump casing adapted to be operatively connected with the carburetor for supplying fuel to said carburetor of said engine, a flexible pumping member in said casing, and means whereby said member makes its pressure stroke by the force of resiliency to vary the supply of fuel automatically with the withdrawal of fuel from said carburetor.

8. A pump comprising in combination a flexible member, means for moving said member positively to provide a suction stroke, and resilient means coacting with 70 said member in moving said member on its pressure stroke, whereby the length of said stroke is determined by the pressure on the fluid being pumped thereby.

9. In a fuel-feeding system for engines, a 75 pump casing adapted to be operatively connected with the source of fuel and the fuel consuming elements, a pump within said casing for supplying fuel to said elements and comprising a flexible pumping member and 80 actuating means for the same so related thereto that said member may move with respect to said means in response to pressure variations in the fuel being pumped thereby.

10. In a fuel-feeding system for engines, 85 in combination, a pump casing adapted to be operatively connected to the source of fuel and the fuel consuming elements, a flexible member in said casing, means for positively flexing said member to provide a suction stroke, said member being movable with respect to said means in response to the pressure of the fuel, and resilient means coacting with said member in moving the same to provide its pressure stroke.

11. A fuel-feeding system for engines comprising means adapted to be operatively connected with a source of fuel, fuel consuming elements for pumping fuel from said source to said elements, said pumping means comprising a flexible member having a stroke which varies automatically to maintain a fixed predetermined pressure on the supply of fuel to said elements.

In testimony whereof I have signed my 105 name to this specification.

JEAN LOUIS LÉON ALEXANDRE ALBERT MOULET.
